UNITED STATES PATENT OFFICE.

HENRY J. GAISMAN, OF WOODMERE, NEW YORK, AND ERNEST W. GRAEF, OF CALDWELL, NEW JERSEY; SAID GRAEF ASSIGNOR TO SAID GAISMAN.

MANIFOLD FOR INTERNAL-COMBUSTION ENGINES.

1,205,614.

Specification of Letters Patent.

Patented Nov. 21, 1916.

Application filed March 13, 1916. Serial No. 83,752.

To all whom it may concern:

Be it known that we, HENRY J. GAISMAN and ERNEST W. GRAEF, citizens of the United States, and residents of Woodmere, in the county of Queens, State of New York, and Caldwell, county of Essex, State of New Jersey, respectively, have invented certain new and useful Improvements in Manifolds for Internal-Combustion Engines, of which the following is a specification.

Our invention pertains to improvements in means for supplying fuel mixtures to internal combustion engines, and has for its object to heat the mixture in its passage from the carbureter to the engine, and to regulate the distance traveled by the mixture in a heated chamber or passage of the manifold according to weather conditions.

Our invention comprises novel details of improvement and combinations of parts that will be more fully hereinafter set forth and then pointed out in the claims.

Reference is to be had to the accompanying drawings forming part hereof, wherein, Fig. 1 is a plan view of our improvements, shown in position upon an engine; Fig. 2 is a side view of the manifold shown in Fig. 1; Fig. 3 is a section substantially on the line 3--3, in Fig. 1; Fig. 4 is a section substantially on the line 4--4, in Fig. 1; Fig. 4^a is a detail of part of the manifold; Fig. 5 is an enlarged horizontal section through the manifold; and Fig. 6 is a section on the line 6--6, in Fig. 5.

Similar numerals of reference indicate corresponding parts in the several views.

The manifold illustrated in the accompanying drawings comprises a casing indicated generally at 1, having a chamber or passage 2 for the flow of heated exhaust gases or products of combustion from an internal combustion engine 3, said casing also having a chamber or passage 4, in thermal relation to the heated gases in chamber 2, for the flow of fuel mixture to the engine cylinder or cylinders from a carbureter 5. Chamber 2 is provided with any desired number of ports or openings 6 communicating with the exhaust ports of the engine, for the flow of exhaust gases from the engine into chamber 2, whence such gases may flow through the outlet 7. By means of cored openings 8 the manifold may be detachably connected with the engine by means of studs or bolts 9 passing through said

cored openings, the walls of said cored openings preventing communication between chambers 2 and 4. The outlets or ports 10 from mixture chamber 4 may communicate with the engine mixture inlet ports in any suitable manner, which outlets are shown in the form of tubular portions 10^a of the casting passing transversely through exhaust chamber 2, whereby the mixture passing through said ports 10^a will come in contact with the heated walls thereof. The specific relation, however, of chambers 2 and 4, so far as our present improvements are concerned, may be varied in a manner well known in the art, provided the two chambers are maintained in thermal relation in the manifold.

The carbureter 5 communicates with chamber 4 and for such purpose said chamber is shown provided with an opening 11, the mixture outlet of the carbureter being shown connected with the manifold by means of a fitting or elbow 12. In the example illustrated one of the studs or bolts 9 passes through the fitting 12 and a nut upon said stud secures said fitting to the manifold. Within chamber 4 is a wall or deflector 13 for the mixture, which is shown extending at one side of and above one of the mixture outlet tubes 10, providing a passage *a* above wall 13, and a space *b* below said wall, whereby the mixture is caused to be diversified in chamber 4, and may flow directly to the righthand outlet 10 (Fig. 3) or reversely under wall 13 to the lefthand outlet 10, as indicated by the arrows in said figure.

The portion of chamber 4 with which the carbureter is in direct communication is shown somewhat enlarged in the nature of a compartment at 14, and one of the objects of our invention is to permit the directing of the mixture from the carbureter into such compartment 14 at such position therein as will cause the mixture to flow in contact with the heated walls of the compartment for a more or less extended distance. For such purpose we have illustrated a mixture deflector 15, in the form of a tubular member provided with an outlet 16 within compartment 14. The outer wall of compartment 14 is shown curved to direct mixture from the closed end or side of the compartment to the passage *a*. The outer end of the tubular member 15 is shown opposing the flange 12^a of the fitting 12, and said member

is shown provided with a flange 15^a bearing against an opposing face of the manifold and fitting 12. The arrangement is such that tubular member 15 may be rotated to 5 any desired position and may be retained in such position by the clamping effect of fitting 12 against flange 15^a forcing the latter against the manifold.

By means of the above described devices, 10 the tubular member 15 may be adjusted relatively in such manner that its outlet 16 may be presented within compartment 14 in any desired position with respect to the passage *a*, and may be retained in such position, 15 whereby the mixture flowing from outlet 16 may be caused to pass through compartment 14 for a distance more or less great. As an illustration of the utility of our improvements, it may be said that if it be desired that the mixture be subjected to the 20 longest possible flow in the heated manifold, as, for instance, in cold weather, then the member 15 may be rotated so that its outlet 16 would be in a position approximately adjacent to the point *c* (Fig. 3) whereby the mixture would be delivered into the compartment 14 at a point remote from the passage *a*, whereby the mixture would flow through the compartment 14 for the greatest 25 distance. If, on the other hand, it be desired that the mixture do not be subjected to such an extended flow in the heated manifold, as, for instance, in warm weather, then the member 15 may be so rotated that its outlet 30 16 will be brought to a position approximately at the point *d* in Fig. 3, close to passage *a*. Hence the mixture flowing from member 15 would not be subjected to such an extent to the heated manifold as when 35 flowing from the point *c*, but would flow directly to the passage *a*. When desired, the member 15 may be so rotated and set that its outlet 16 will be presented at any other 40 point in compartment 14 between the extremes *c* and *d*, to regulate the flow of the mixture through compartment 14 to the desired extent according to weather conditions 45 that may vary between cold and warm weather. The member 15 may be provided 50 with a pointer or index 17, set with relation to outlet 16, and the manifold may be provided with indicating points 18 to which the pointer 17 may be set (Fig. 2) according 55 to the desired position to which outlet 16 is intended to be adjusted.

Changes may be made in the details of construction and arrangement of parts set forth, as the same may be varied, within the scope of the appended claims, without departing from the spirit of the invention.

Having now described our invention what we claim is:

1. A manifold comprising a passage for 60 exhaust gases and a passage for fuel mixture in thermal relation thereto, and means

to admit fuel mixture into the mixture passage at different points thereof for a longer or shorter course through said passage.

2. A manifold comprising a passage for 70 exhaust gases and a passage for fuel mixture in thermal relation thereto, said mixture passage having a mixture receiving compartment, and means to admit fuel mixture at different points of said compartment to permit the flow therethrough of mixture 75 for a greater or less extent.

3. A manifold comprising a passage for 80 exhaust gases and a passage for fuel mixture in thermal relation thereto, said mixture passage having a compartment communicating at one end therewith and curved with respect to said passage, the opposite end of said compartment being closed, and means to admit fuel mixture to said compartment at different distances along the 85 same to cause said mixture to traverse said compartment to a greater or less extent.

4. A manifold comprising a passage for 90 exhaust gases and a passage for fuel mixture in thermal relation thereto, and an adjustable element for communication with a carburetor and provided with an outlet communicating with said passage whereby fuel mixture may be directed for a longer or shorter course in said passage.

5. A manifold comprising a passage for 100 exhaust gases and a passage for fuel mixture in thermal relation thereto, and a tubular member movably supported in said passage and adapted for communication with a carburetor, said member having a mixture outlet communicating with said passage whereby the fuel mixture may be admitted into said passage at different points to provide a shorter or longer course within the 105 passage for such mixture.

6. A manifold comprising a passage for 110 exhaust gases and a passage for fuel mixture in thermal relation thereto, and a tubular member movably supported in said passage and adapted for communication with a carburetor, said member having a mixture outlet communicating with said passage whereby the fuel mixture may be admitted into said passage at different points to provide a shorter or longer course within the passage for such mixture, and means to connect the carburetor outlet with said tubular member and retain the latter in set position.

7. A manifold comprising a passage for 120 exhaust gases and a passage for fuel mixture in thermal relation thereto, said mixture passage having a plurality of outlets, a wall within said mixture passage extending to a point between two outlets providing mixture passages on opposite sides of a mixture outlet, and an adjustable tubular member having a mixture outlet and located in said mixture passage at one side of said 125

outlet to direct mixture to one of said passages for a longer or shorter course in said passage.

8. A manifold comprising a passage for fuel mixture, means to heat said passage, and means to admit fuel mixture into the mixture passage at different points thereof for a longer or shorter course through said mixture passage.

10 9. A manifold comprising a mixture passage, means to heat said passage, an inlet for fuel mixture adjacent to one end of said passage, and means to vary the point of delivery of mixture from said outlet into

15 said mixture passage to subject the mixture to a longer or shorter course through said passage.

10. A passage for exhaust gases and a passage for fuel mixture in thermal relation thereto, and means to admit fuel mixture into the mixture passage for a longer or shorter course through said passage.

20 11. A passage for exhaust gases and a passage for fuel mixture in thermal rela-

tion thereto, and means to subject fuel mixture in the mixture passage to a greater or lesser contact with a heated surface therein.

12. A passage for fuel mixture, means to heat said passage, and means to subject fuel mixture in the mixture passage to a greater 30 or lesser contact with a heated surface therein.

13. A passage for fuel mixture, means to heat said passage, and means to admit fuel mixture into the mixture passage at different points thereof for a longer or shorter course through said passage.

14. A passage for exhaust gases having a curved portion, means to heat said passage, and means to admit fuel mixture into the 40 curved portion of the passage for a longer or shorter course through the passage.

Signed at New York city, in the county of New York, and State of New York, this 11th day of March, 1916.

HENRY J. GAISMAN.
ERNEST W. GRAEF.
